FIG. 4.

UNITED STATES PATENT OFFICE

2,013,533

PRINTING MECHANISM

Eugene Buhler, New York, N. Y., assignor, by
mesne assignments, to International Business
Machines Corporation, New York, N. Y., a cor-
poration of New York

Application July 10, 1931, Serial No. 549,881

15 Claims. (Cl. 101—93)

The invention relates to accounting machines and has for its principal object the provision of an improved printing mechanism for such machines.

Another object of the invention resides in the simplification of the printing mechanism of such machines by the provision of a constantly rotating type drum and the provision of a power actuated impression hammer for striking an impression from a type while the drum is in motion.

Other objects reside in new and improved structures and cooperations of the several elements of the mechanism as will be pointed out in the following detailed description.

The preferred form of the invention contemplates a constantly rotating type carrier having a plurality of type movable in succession past a printing position. A power actuated impression hammer is adapted to be impelled against any of the type as such type is passing printing position, the timing of the hammer movement and the arrival of a selected type at printing position being positively synchronized to the actual contact point.

The invention is illustrated by way of example in the accompanying drawings in which

Fig. 1 is a cross sectional view of the mechanical structure.

Fig. 2 is a position view of parts shown in Fig. 1.

Fig. 3 is a modified form of mechanism.

Fig. 4 shows a circuit diagram of a tabulating machine to which the printing device may be applied.

The circuit diagram in Fig. 4 is substantially that of the printing tabulator disclosed in the patent to Daly and Page, #1,762,145, issued June 10, 1930. During adding operations the machine is driven by a tabulating motor TM which is controlled by a group of circuits including relays and cam contacts and indicated generally at TC. The usual card feed clutch magnet is shown at CF in series with the tabulating motor and is effective to feed the usual perforated cards as long as the tabulating motor is in operation.

The cards feed successively past the upper analyzing brushes UB and the lower analyzing brushes LB and as they pass the latter the items represented by the perforations may be entered into accumulators represented by counter magnets 10 and printed by printer magnets 11. The cards continue to feed and the successive items to be entered as long as certain classification perforations on successive cards do not

change, this being taken care of by the usual group control system indicated generally at GC. On a change in the group classification perforations, the group control system interrupts accumulating and a total taking operation may be initiated, the machine in this instance being driven by the reset motor RM under control of a group of circuits indicated generally at RC. The printing in this case also is controlled by the printing magnets 11. These operations are well understood and fully explained in the patent referred to above.

Each card column contains ten index point positions differentially located to represent the ten digits and a different digit is represented by a perforation in each position. As the card passes the lower brushes LB the position of its index points determines the time of the closure of circuits through the analyzing brushes and the resulting current impulses may energize selected counter magnets 10 when the latter are properly plugged to the lower analyzing brushes. The magnets 10 when thus momentarily energized effect clutching action between an accumulating wheel and a constantly operating driving shaft which clutching action persists until a predetermined point in the machine cycle. The amounts represented by the perforations are thus rolled into the accumulators.

The magnets 10 when energized open contacts 12 to break their own circuits and close contacts 13 to energize print magnets 11 at a time in the cycle corresponding to the value of the item entered in the accumulators. Total printing is controlled by contacts 14 which cooperate with stepped cams 15. The latter are positioned by the accumulator wheels and the steps are so arranged that when the contacts 14 are operated during total taking they will be closed at a time in the cycle corresponding to the items standing on the accumulators, and energize print magnets 11 at this time.

A shaft 20 (Fig. 1) is suitably geared to the main drive shaft of the tabulator so as to rotate constantly therewith and make one revolution for each cycle of operation of the tabulator. Driven from shaft 20 through gearing designated generally at 21 is a shaft 22 which has secured thereto a printing drum 23. Disposed on opposite sides of the drum 23 are duplicate sets of printing type 24 which rotate with the drum and a set of such duplicate type is provided for each column of the record which is to be printed. A stationary circular shield or casing 25 fixedly secured to the frame of the device is disposed about the print-

ing drum and is provided with an opening 26 through which printing is effected upon a record strip 27. The strip 27 is fed from a supply reel 28 and around shield 25 to a pair of feed rollers 29 and 30. The former is adapted to be rotated slightly to effect line spacing by means of a pawl mechanism generally designated 31 cooperating with ratchet 32 rigidly secured to the shaft of roller 29. The ratchet actuating mechanism 31 is adapted to be operated by a cam 33 secured to shaft 22.

The usual printing ribbon 34 is suitably guided between record strip 27 and type elements 24 and may be suitably advanced by mechanism not shown in detail. A printing hammer 35, one of which is provided for each column, is adapted to be positively impelled toward the printing drum 23 during the movement of the type past printing position. This action takes place under control of the printing magnet 11 in the following manner: Secured upon constantly rotating shaft 20 is a fluted or toothed actuating member 36 having teeth 37 adapted to cooperate with a tooth 38 in an arm 39 which is pivoted to the lower extremity of a lever 40 pivoted at 41. Carried by arm 39 is a stud 42 adapted to be engaged by a spring-pressed by-pass 43 carried on lever 44.

Energization of magnet 11 through its armature 45 and link 46 will rock spring-pressed latch 47 in a clockwise direction releasing lever 44 for movement in a counterclockwise direction under the combined influence of its spring 48. The consequent depression of by-pass 43 and its engagement with stud 42 will move the tooth 38 into engagement with a tooth 37 of actuating member 36 whereupon the member 39 will be moved in a positive manner toward the right, rocking lever 40 about its pivot 41. The upper extremity of lever 40 is adapted to engage a depending arm of hammer 35 and rock the hammer in a clockwise direction about its pivot 50. As arm 39 is moved toward the right the free end thereof is adapted to engage the inclined camming surface 51 which serves to disengage tooth 38 from the actuating member 36. This disengagement will take place when the parts are substantially in the position shown in Fig. 2 at which time the lever 49 will have positively rocked the printing hammer 35 so that its striking point is just about to make contact with the record strip. The momentum of the hammer will carry it forward from this point to make actual printing contact between the record strip and a type element 24 after which it will rebound to home position where it is restrained by its spring 52.

The gearing is such that the type elements 24 pass printing position in synchronism with the passage of the index point positions of the record card past the analyzing brushes of the tabulating machine and the teeth 37 in the actuator 36 are so arranged that a tooth will pass the tooth 38 during the passage of a type 24 past the printing line. When all of the type 24 in either set have passed printing position a cam 53 mounted on shaft 20 is adapted through spring-pressed linkage 54 to rock the shaft 55 to cause depression of restoring fingers or bail 56 mounted on shaft 55.

Counterclockwise rocking of finger 56 will restore lever 44 to its normal position and through extension 49 will also cause positive restoration of latch 47 and its connected link 46 and armature 45. Upon release of arm 39 from actuator 36 the arm is held upwardly and moved toward the left together with lever 40 by spring 57. By-pass 43 is so constructed as to offer no resistance to the

restoration of arm 39 if the lever 44 has not been relatched. Now when lever 44 is rocked clockwise and relatched, the by-pass 43 will snap back over stud 42 to the position of Fig. 1.

A modified form of latching structure is shown in Fig. 3 wherein energization of magnet 11 will rock a latch 47a in a counterclockwise direction so that a projection 49a thereon will depress lever 44a to move arm 39a into engagement with actuator 36. During the movement to the right of 10 arm 39a under the action of actuator 36, a camming edge 58 integral with arm 39a will engage lever 44a rocking the same about its pivot to latched position at the same time positively restoring latch 47 together with the armature of 15 magnet 11. In this manner the lever 44a and latch 47a are restored concurrently with the actuation of the type hammer 35.

While there has been shown and described and pointed out the fundamental novel features of 20 the invention as applied to a single modification, it will be understood that various omissions and substitutions and changes in the form and details of the device illustrated and in its operation may be made by those skilled in the art without 25 departing from the spirit of the invention. It is the intention therefore to be limited only as indicated by the scope of the following claims.

I claim:

1. In a printing mechanism, a rotatable type 30 carrier, a printing hammer, a power drive, and an actuator for connecting said power drive with said hammer during rotation of said carrier to impel said hammer against the carrier.
2. In a printing mechanism, a rotatable type 35 carrier, a printing hammer cooperating therewith, a power drive, means adapted to connect said hammer to said power drive to cause movement of said hammer against said carrier while the carrier is in motion and further means for 40 disconnecting said hammer from said drive before said hammer strikes said carrier.
3. In a printing mechanism, a type carrier comprising a plurality of type elements, means for moving said elements through printing position successively, a power actuator, a printing hammer coupling means for connecting said hammer to said actuator to cause said hammer to be actuated against said type elements as said elements are passing printing position and means 45 for synchronizing the actuation of said hammer and the movement of said type elements past printing position to cause printing from a predetermined one of said type elements.
4. In a printing mechanism, a rotatable ele- 55 ment, a type member carried by said element and adapted to be moved past printing position, a hammer, and actuating means adapted to cause said hammer to strike said type member as said member is moving past printing position, said 60 hammer being free from control of said actuating means at the time when the said hammer is striking the type member.
5. In a listing machine, card perforation reading means, a continuously rotatable element, a 65 type member carried by said element, a hammer adapted to cooperate with said member and means controlled by said reading means for positively actuating said hammer against said member during the continuous rotation of said ele- 70 ment.
6. In a listing machine, a plurality of type members, means for continuously moving said members through a predetermined printing position, a power actuated printing hammer and 75

- means for causing a positive power actuation of said hammer for selectively printing from one of said members while said members are passing through said printing position.
- 5 7. In a printing machine adapted to be controlled by data-containing means, data sensing elements, type members, means for causing said members to move continuously toward a fixed printing position, a printing hammer, and means controlled by said sensing elements for positively moving said hammer against said members for selectively printing from said members while the latter are passing through said printing position.
- 10 8. In a printing machine of the class controlled by perforated cards, a rotatable drum and means for rotating the same, a plurality of type characters circumferentially disposed on said drum, a printing hammer disposed adjacent to said drum, said drum and hammer being adapted to receive a record strip therebetween, and card-controlled means for selectively urging one of said characters and said hammer together when such character occupies a predetermined position and while said drum rotates uninterrupted whereby said character is impressed upon said record strip during the uninterrupted movement of said drum.
- 15 9. In a machine adapted to be controlled by record cards having index points thereon, means for cooperating with the index points of said cards, means for feeding cards past said cooperating means, a plurality of type members, means for moving said members through a predetermined printing position synchronously with the feeding of such cards, a printing hammer, an actuator therefor and means controlled by said cooperating means for connecting said hammer to said actuator for selectively printing from said members when the latter are passing through said printing position.
- 20 10. In a machine adapted to be controlled by record sheets having index points thereon, means for cooperating with the record sheet index points, means for feeding the record sheets past said cooperating means, a plurality of type members of varying designations arranged to correspond in relative positions and designations with the index points of a sheet, means for moving said members past a predetermined printing line in synchronism with the movement of the index points of a sheet past said cooperating means, a printing hammer, and means controlled by said cooperating means for positively moving said
- hammer into striking engagement with any of said members while the latter are passing through said printing line.
11. In a printing mechanism, a movable type carrier having a plurality of type elements thereon, a printing hammer, a power drive, an actuator for connecting said power drive with said hammer during movement of said carrier to impel said hammer against the carrier.
- 15 12. A printing mechanism comprising a movable type carrier having a plurality of type elements thereon, means for moving said carrier, a printing hammer, means for connecting said hammer to said moving means effecting movement of said hammer toward one of said elements, means for disconnecting said hammer from said moving means after partial movement thereof, said hammer being adapted to continue its movement and strike said moving element by virtue of the momentum acquired during said 20 partial movement.
13. In a printing mechanism, a type carrier, having a plurality of columns of type arranged in rows, a plurality of printing hammers, one for each column of type, means for concurrently moving said columns past a printing position whereby the rows pass said position in succession, a record positioned between said carrier and said hammers, a power drive and means for selectively connecting said hammers to said power 30 drive at different times to force the record against the carrier at such times to receive a succession of impressions on a single line as the rows of type pass uninterruptedly through printing position.
14. The invention set forth in claim 13 in which means is provided for advancing the record after all the rows of type have passed through printing position.
15. In a printing mechanism, a type carrier having a plurality of type elements thereon, an actuator having a plurality of actuating elements, one for each type element on the carrier, means for imparting a continuous movement to both the carrier and the actuator, a pivoted printing hammer adapted to cooperate with said type elements and means for selectively coupling said hammer to one of said actuating elements to cause the hammer to be positively rocked into engagement with the type element corresponding to the selected actuating element to cause printing therefrom.

EUGENE BUHLER.
